DRAFTING MECHANISM FOR TEXTILE
SPINNING MACHINES

Konrad Eberle, Flums, Switzerland

Filed Apr. 20, 1959, Ser. No. 807,358

Claims priority, application Switzerland Apr. 21, 1958
1 Claim. (Cl. 19—258)

The present invention relates to drafting mechanisms for textile spinning machines.

Spinning machines with drafting or grooved rollers which have asymmetrically profiled grooves are already known, but with these rollers a bottom belt of the machine has been looped about the relevant roller and the asymmetrical profile has been provided for the purpose of improving the entrainment of a top roller bearing against the belt. Moreover, it has already been proposed to provide asymmetrically profiled grooving on drafting rollers which each co-operate with a sliding weighting member adapted in shape thereto.

According to the present invention there is provided a drafting roller, which is arranged in a drafting zone and is in contact with the fibrous material, with grooving orientated in a direction opposite to the direction of action of the drafting force. In this way, the material is better held back than by the conventional arrangements.

An embodiment of the invention will be explained with reference to the accompanying drawings in which:

FIG. 1 illustrates a drafting zone of a drafting mechanism, and

FIG. 2 is a view on a larger scale, of the grooving of a delivery roller in the drafting zone illustrated in FIG. 1.

FIGURE 1 illustrates a drafting zone which is bounded by the nips between a rapidly rotating pair of drafting rollers 1, 2 and a slowly rotating pair of drafting rollers 3, 4. The lower drafting rollers 2 and 4 are provided with asymmetric grooving.

The nip between the rollers 1 and 2 is shown on a larger scale in FIG. 2. Two radii S and S' extending from the centre of the roller 2 are drawn through bottom corners 5 and 6, respectively, of an individual groove or flute 7. The adjoining walls of the groove 7 are inclined at angles

2

α and β with respect to the radii S and S', respectively. The angle α is greater than β , i.e. the rear wall 9 is substantially radial whereas the forward wall 8 is inclined forwardly with respect to the direction of circumferential movement of the rollers 2. The result is that the grooving is forwardly inclined or orientated in the direction of rotation of the roller. Since the rollers 1 and 2 rotate faster than the rollers 3 and 4, the rather steep rear walls 9 of the flutes produce a relatively firm grip on the fibrous material whereas the inclined forward walls 8 of the flutes afford a smooth release or disengagement of the material from the grooves 7. In the case of the entry or feed roller 4, the fluting must, as shown in FIG. 1, be orientated in the direction opposite to the direction of rotation, in order that it will be in opposition to the direction of action of the drafting force in the drafting zone.

What is claimed is:

In a textile drafting arrangement, a forward drafting roller, a rearward drafting roller spaced from said forward drafting roller, and a pressure roller cooperating with each of said drafting rollers to form two spaced nips of a drafting zone, said drafting rollers being axially fluted, the flutes of the forward drafting roller having a rear wall with respect to the direction of the circumferential movement of the flutes, said rear wall being substantially radial, the flutes of the forward drafting roller having a forward wall which is forwardly inclined with respect to the direction of the circumferential movement of the flutes, the flutes of the rearward drafting roller having a forward wall with respect to the direction of the circumferential movement of the flutes, said forward wall being substantially radial, the flutes of the rearward drafting roller having a rear wall which is rearwardly inclined with respect to the circumferential movement of the flutes.
